(57) **CLAIM**

The ornamental design for a utensil for holding an object in a liquid bath, as shown and described.

DESCRIPTION

FIG. 1 is an isometric view of a utensil for holding an object in a liquid bath showing my new design.

FIG. 2 is a rear elevational view thereof.

FIG. 3 is a top plan view thereof.

FIG. 4 is a left side elevational view thereof, the right side elevational view being a mirror image thereof.

FIG. 5 is a front elevational view thereof; and,

FIG. 6 is a bottom plan view thereof.

The broken lines showing an object and a suction cup are for illustrative purposes only and form no part of the claimed design.
